UNITED STATES PATENT OFFICE

SAMUEL A. NEIDICH, OF EDGEWATER PARK, NEW JERSEY, ASSIGNOR TO SYLVANIA INDUSTRIAL CORPORATION, OF FREDERICKSBURG, VIRGINIA, A CORPORATION OF VIRGINIA

LIFTING AND ROTATING APPARATUS

Original application filed February 12, 1929, Serial No. 339,470. Divided and this application filed August 5, 1932. Serial No. 627,598.

This is a division of my copending application for Letters Patent of the United States, Serial No. 339,470, filed February 12, 1929, for improvement in viscose treating apparatus.

5 My invention relates to apparatus of the type claimed in Letters Patent of the United States No. 1,616,918 granted to me February 8, 1927; wherein a rotary carriage is arranged to support a circular series of receptacles, each adapted to receive trays of viscose filaments, and liquids for treating them; said carriage being turned to successively subject such filaments to the action 10 of the different liquids, which are successively supplied to and discharged from said receptacles by the automatic operation of series of valves.

The form of my invention herein disclosed 20 differs from that of said Letters Patent, in that bodies of the several liquids aforesaid are continuously maintained in respective stationary tubs, and the rotary carriage is arranged to support the filament trays independently of the liquid containers, and to not only intermittently turn to present the trays 25 in registry with such stationary tubs, in succession, but to be lowered and raised to successively submerge the filaments in the liquids 30 in said tubs and raise the filaments therefrom. As hereinafter described, the means for raising and lowering said carriage is adapted to repeatedly dip the filaments up and down in the liquids in the tubs, to cause the 35 liquids to surge through the filaments in the tubs.

The several features of my present invention, differing from that disclosed in said Letters Patent, are advantageous in that the 40 cost of construction of the apparatus is very much less and the operation thereof is facilitated.

45 My invention includes the various novel features of construction and arrangement hereinafter more definitely specified.

In said drawings; Fig. I is a plan view of said rotary carriage, the circular series of tubs subjacent thereto, and their appurte- 50 nances.

Fig. II is a plan view of the lifting mech-

anism for turning and lowering said rotary tray carriage.

Fig. III is a side elevation of said mechanism shown in Fig. II.

Fig. IV is a transverse sectional view of 55 said mechanism, taken on the lines IV, IV, in Figs. II and III, in the direction of the arrows on said lines.

Fig. V is a diagram of the electric circuits of said apparatus.

Referring to Fig. I; in the use of said apparatus in a process of converting and dyeing viscose filaments, a circular series of eighteen tanks or tubs 1, for containing liquids, is so organized that treatment of the 60 filaments may be effected during a cycle of operation of the apparatus. The filaments to be treated may be conveniently held in trays which may be supported upon a pair of opposed angle rails 2, which are conveniently formed of porcelain or other ceramic material. Each pair of such rails 2 is suspended by hangers 3, which are pendent from tray supporting frames 5 which are 65 positively fixed upon the rotary carriage 65, which is rigidly connected with the vertical shaft 66 by which said carriage and its appurtenances, including the trays of filaments, are raised, lowered, and turned from tub to tub in the circular series.

Referring to Figs. II to V; said rotary carriage shaft 66 is mounted for rotation and vertical reciprocation in the bearing 71; which bearing is in the stationary housing 72 and has the lubricating oil pocket 73 above 75 it and the felt packing 74 below it, to limit leakage of the oil down said shaft. Said shaft is also mounted for rotation and vertical reciprocation in the bearing bracket 75 on the base plate 76 which is stationary on a scaffolding 77. Said base plate 76 has the roller bearing 80 for said shaft and supports the worm gear 81 which is mounted to turn freely in the roller bearings 82 and 83 between said bracket 75 and base plate 76. Said gear 85 has a key 85 extending in the key way 86 in the portion of said shaft 66 which reciprocates through said worm gear 81; whereby said shaft may be turned without interference with its vertical reciprocation.

Said rotary carriage shaft 66 has the collar 87 rigidly connected therewith and by which it is raised and lowered by means of the lever 88 which is fulcrumed at 89 on the bracket 90 5 rigidly connected with said base plate 76. Said lever 88 includes the fork 91 carrying opposite rollers 92 upon which said shaft collar 87 continually rests. The weight of said shaft 66 and its appurtenances including 10 said carriage 65 etc., is almost completely counterbalanced by the weights 94 which are carried by the link 95 at the end of said lever 88 opposite to said shaft 66. The weight of said shaft and its appurtenances, not thus 15 counterbalanced, is borne by the rotary cam 96 which is ridden by the rollers 97 on said lever 88. Said cam 96 is of such configuration that every desired vertical movement of said shaft 66 and the filament carriage supported by it, is effected in proper sequence 20 with the intermittent rotary movement of said shaft. The relative rotary movements of said shaft 66 and cam 96 are conveniently effected by the driving shaft 99 which may 25 be constantly rotated by connection with a suitable motor and which has, rigidly connected therewith, the crown clutch member 100. Intermittent rotary movement of said shaft 66 and cam 96 is obtained from the 30 continuous rotary movement of said shaft 99, by means of the crown clutch member 101, which is mounted to slide axially upon the shaft 102 which is journaled, in axial alignment with said shaft 99, in the bearings 104 35 and 105 on said base plate 76. Axial movement of said clutch member 101 to engage and disengage said clutch member 100, is effected by the lever 107 which is fulcrumed at 108 on said base plate 76, has a stud 109 40 engaging the groove 110 in said clutch member 101, and is connected by the link 111 with the lever 112 which is fulcrumed at 113. Said shaft 102 carries the worm 115 continually 45 engaged with said worm gear 81, whereby said carriage shaft may be intermittently turned; when said worm is operatively connected with its shaft 102 by its friction clutch 116, as hereinafter described.

Said shaft 102 also carries, rigidly connected therewith, the worm 117, continually 50 engaged with the worm gear 118 on the cam shaft 120 with which said cam 96 is rigidly connected. The construction and arrangement of the driving mechanism aforesaid are 55 such that said cam shaft 120 is continually turned clockwise as indicated in Fig. III, and the carriage 65 is turned clockwise as indicated in Fig. I, whenever the clutch member 101 is engaged with the driving clutch member 100 on the shaft 99.

Said cam shaft 120 carries the cam 121 60 having the roller 122 in cooperative relation with the clutch lever 123 which is mounted on the rock shaft 124 journaled in the bearings 125 and 126 which are stationary on said

base plate 76. Said clutch lever 123 has the roller 128 engaged in the groove 129 on the clutch member 130 which is thereby axially movable on said shaft 102. Clockwise movement of said cam shaft 120, as indicated in Fig. III, causes the roller 122 on said cam 121 to intermittently encounter said clutch lever 123, push it down out of the path of said roller 122, and thus move said clutch member 130 to the right in Fig. III; thus 70 engaging said clutch member 116 to frictionally engage said worm 115 with said shaft 102 to effect the intermittent turning movement of said carriage shaft 66, at the proper time in the cycle of operation of said carriage 65. Said clutch lever 123 also has the roller 132 which rides upon the annular flange 133 of said clutch member 116 and is adapted to drop into the notch 134 of said disk when said clutch member 130 is in the 80 disengaged position shown in Fig. III. The construction and arrangement of the various elements aforesaid by which said flange 133 is turned, are such that when its notch 134 is thus engaged by the clutch lever roller 132; 90 the porcelain rails 2, carrying the filament trays, are in registry with the respective tubs 1, in which said filaments are to be dipped.

However, as a safety device, to prevent accidental lowering of the carriage 65 and its 95 appurtenances when said tracks 2 are not in proper registry with said tubs 1, I provide the slide bolt 136 which is mounted to reciprocate horizontally in the bearings 137 and is operatively connected with the arm 138 of said clutch lever 123, by the bell crank lever 139 and link 140; so that, when said roller 132 is uplifted from the notch 134 of the clutch flange 133, said bolt 136 is thrust 100 away from the observer in Fig. III and beneath said lever 88 so as to uphold the latter and the unbalanced portion of the weight of the carriage 65 and its appurtenances until said roller 132 falls into said notch 134, when the latter is again presented in registry 105 therewith. Said slide bolt 136 thus prevents lowering movement of said carriage 65 and its appurtenances except when the porcelain tracks 2 are properly registered with their respective tubs 1.

Moreover, I prefer to provide said apparatus with means to automatically stop the 110 operation of the machine by the shaft 102; if and when said roller 132 fails to drop into the notch 134 of the clutch flange 133 at the proper time. Such means includes the arm 142 on the clutch lever 107 and the weight 143 which, when released, drops upon said arm 142 and shifts the clutch member 101 to the left in Fig. III, by said lever 107. Said weight 143 is conveniently upheld by the solenoid coil 144 which is energized by the circuit including the conductors 145 and 146. Said circuit includes the two push switches 148 and 149 which are spring pressed so as to 115 120 125 130

be normally closed, in parallel relation with each other but in series with said coil 144. As long as either of said switches remains closed, the circuit energizing said coil 144 is closed and the weight 143 upheld. Either of said switches may be pushed to open the circuit thereat, without dropping the weight, but if both switches are contemporaneously operated to open the circuit, said weight 10 drops and the machine stops. Said switch 148 is arranged to be operated by the lever 151 which is rigidly connected with the rock shaft 124, so that the circuit is opened at said switch 148 whenever said roller 132 is 15 uplifted from the notch 134 to roll upon the clutch flange 133 as the latter turns. The switch 149 is arranged to be operated by the roller 152 on the arm 153 which is rigidly connected with the cam shaft 120. Said arm 20 153 is so positioned on said shaft that said roller 152 pushes upon the switch 149 immediately after said notch 134 has been presented in registry with said roller 132; so that, if the switch 148 has not been permitted 25 to close by the fall of said roller 132 into said notch, and consequent withdrawal of the arm 151 from said switch 148; the circuit remains open at that switch and is, thereupon, immediately opened at the other switch 149, so 30 that the circuit energizing said coil 144 is broken and the weight released to stop the apparatus as aforesaid.

As the action of the worms on said shaft 102 tends to thrust the latter axially to the left in Fig. III, the bearing 105 includes anti-friction balls or other rollers to sustain such stress and minimize the friction incident thereto. Moreover, I find it convenient to lubricate the lower end of the shaft 66 and 40 the worm gear 81 and worm 115 connected therewith, by mounting upon the under side of said base plate 76, the oil well 156 into which the lower end of said shaft 66 dips and forces oil upwardly, to said parts, each 45 time said shaft is lowered.

However, I do not desire to limit myself to the specific construction and arrangement herein set forth, as it is obvious that various modifications may be made therein without 50 departing from the essential features of my invention, as defined in the appended claims.

I claim:

1. The combination of a vertically movable carriage; means to automatically intermittently raise and lower said carriage; means to automatically intermittently turn said carriage; wherein the means to raise and lower said carriage includes a cam having a plurality of crests, and wherein said carriage is carried by a vertically reciprocating shaft; a collar rigidly connected with said shaft; a lever arm fulcrumed on an axis at right angles to the axis of said vertical shaft and bearing against said collar; and means carried by 60 said lever arm for cooperation with said cam; 65

whereby said carriage is raised and lowered by rotation of said cam.

2. The combination of a vertically movable carriage; means to automatically intermittently raise and lower said carriage; means to automatically intermittently turn said carriage; wherein the means to raise and lower said carriage includes a cam having a plurality of crests, and wherein said carriage is carried by a vertically reciprocating shaft; a collar rigidly connected with said shaft; a lever arm fulcrumed on an axis at right angles to the axis of said vertical shaft; roller means on one end of said lever arm bearing against said collar; means at the other end of said arm almost counterbalancing the weight of said vertical shaft and its appurtenances; whereby said carriage is raised and lowered by rotation of said cam. 70 75

3. The combination of a vertically movable carriage; means to automatically intermittently raise and lower said carriage; means to automatically intermittently turn said carriage; wherein the means to raise and lower said carriage includes a cam having a plurality of crests, and wherein said carriage is carried by a vertical reciprocating shaft; a collar rigidly connected with said shaft; a lever arm fulcrumed on an axis at right angles to the axis of said shaft and bearing against said collar; means carried by said arm for cooperation with said cam; and carriage turning means including a worm gearing operatively connected with said cam by a clutch, and including another eccentric, arranged to turn with said cam, and effect intermittent operation of said clutch. 80 85 90 95

In testimony whereof, I have hereunto signed my name at Burlington, New Jersey, this third day of August, 1932.

SAMUEL A. NEIDICH.
